UNITED STATES PATENT OFFICE.

PETER KNUDSEN, OF HETLAND, SOUTH DAKOTA.

SEED-POTATO CUTTER.

Application filed May 15, 1924. Serial No. 713,575.

To all whom it may concern:

Be it known that I, PETER KNUDSEN, a citizen of the United States, residing at Hetland, in the county of Kingsbury and State of South Dakota, have invented certain new and useful Improvements in a Seed-Potato Cutter, of which the following is a specification.

The present invention relates to vegetable cutting machines, and more particularly to that type of cutting machines adapted to cut seed potatoes into relatively large pieces suitable for planting.

An object of this invention is to provide a strong and simple device which may be operated by hand or other power, and which will effectively cut potatoes into the desired number of pieces for planting in the ground.

Another object of this invention is to provide a cutter having a reciprocal movement and which will cut potatoes at both the forward and return movement of the device.

A further object of this invention is to provide means for separating the potatoes of various sizes, and for cutting the larger sized potatoes into a greater number of pieces than the smaller potatoes, the final cut pieces being substantially uniform in size irrespective of the initial sizes of the potatoes before being cut.

The above and various other objects and advantages of this invention will in part be described in and in part be understood from the following detailed description of the present preferred embodiment, the same being illustrated in the accompanying drawings, wherein:

Fig. 1 is a side elevation of a device constructed according to this invention.

Fig. 2 is a top plan view of the device, looking downwardly.

Fig. 3 is a top plan view with the tray removed and the pistons in retracted position.

Fig. 4 is an end elevation showing the arrangement of the cutters.

Fig. 5 is a transverse section taken through the device on substantially line 5—5 of Fig. 1, and

Fig. 6 is an enlarged longitudinal sectional view showing the detailed construction of the pistons which force the potatoes against the cutting devices.

Referring to the drawings, and first to Figs. 1 to 3, inclusive, the device is mounted on a frame having legs or posts 10 which are

preferably made of metal and at their lower ends are bent outwardly to provide an adequate base which if desired may be secured to a floor by bolts or the like. The upper ends of the legs 10 are bent inwardly and have secured to their upper surfaces side bars 11 which hold the forward and rear legs in spaced relation to each other. In order to make the side bars rigid and to hold the legs 10 at right angles to the side bars 11, angular braces 12 have been provided, each being fastened at one end to one of the legs 10 and at the other end to a side bar 11. There have also been provided forward and rear open frames 13 which extend between the side bars and are secured to the upper faces of the side bars.

A sorting table 14 having upstanding sides, is secured at one end to the frame 13 intermediate the ends of the latter. The table 14 is inclined over the frame so that when potatoes are placed therein they will gravitate toward the forward end of the table 14. The table 14 is held in rigid position by a pair of braces 15 which are bolted or otherwise fastened at their upper ends to the lower side of the table 14, preferably at a point spaced inwardly from the rear end of the table, and at their lower ends to the side bars 11. The table 14 has across its inner end an end piece 16 which is preferably of metal and which has its outer ends bent at substantially right angles to the end of the table so as to engage the upstanding sides of the table 14 to which the end piece 16 is attached by screws, bolts or the like. The end piece 16 is also provided with a pair of angular legs 17 which are secured to the frame by bolts or the like.

The bottom of the table 14, at the inner end thereof, is provided with a series of openings 18 which are preferably of different sizes to accommodate the various sizes of potatoes. The openings 18 are separated by a plurality of space bars 19 which are secured at their forward ends to the end piece 16 and at their rear ends to the bottom of the table 14. Immediately below the openings 18 there is provided a series of substantially tubular chambers 20 which are secured to the frame and which have openings in their upper surfaces corresponding to the openings in the table 14 to permit the dropping of potatoes into the chambers. The chambers 20 have each an opening 21 in its lower side, so that any dirt or foreign mat-

ter adhering to the potatoes and becoming loose therefrom will fall through the openings and prevent clogging of the device. A plurality of spring fingers 22 are secured at 5 their inner ends to the chambers 20 and radially arranged with respect thereto, and have their outer ends extending into the open frames 13 and free so that the fingers can have yielding engagement with potatoes 10 as the potatoes are forced through tapered tubular passages defined by the fingers. A plurality of pistons 25 is provided, said pistons being of different sizes corresponding to the different sizes of openings in the 15 chambers 20, and are attached to a crossbar 26 which is preferably flat and which extends beyond the outer sides of the frame. The lower side of the crossbar 26 slidably rests upon the side bars 11, and the upper side slidably engages a bar 27 which is secured to the side bar 11 by bolts or the like and held in spaced relation thereto by spacers 28.

A crankshaft 29 is provided at one end of 25 the frame and is held in a bearing 30 which is secured to the frame and is preferably in two pieces to permit the taking up of wear in the bearing. The crankshaft 29 is provided with cranks at both ends which 30 are directly opposite one another. A pair of connecting rods 31 engage at one end the cranks 29 and at their other end the outer ends of the crossbar 26 so that when the cranks are turned the pistons 25 will move 35 backward and forward.

It will be seen that this device is very simple and easy to operate and if desired may be operated by hand, but as the device 40 will probably only be used by persons having a great many potatoes to cut, and in order to speed up the cutting thereof, a counter shaft 32 is provided and is seated in the bearing member 30 at a predetermined distance below the crankshaft 29. A smaller 45 gear 33 is secured to the shaft 32 and meshes with a larger gear 34 on the shaft 29. Power is transmitted to the shaft 32 from any suitable source of supply, and is preferably transmitted by a belt which turns a pulley 35 which is secured to the shaft 32.

A plurality of knives 36 and 36' are carried by the frames 13 with their knife edges extending inwardly for cutting engagement with potatoes forced through the passages 50 defined by the fingers. The knife 36' extends in crossed relation to the knives 36 and is preferably arranged slightly inwardly from the knives 36, and acts as a guide for the pistons in addition to cutting the potatoes in two pieces, as the pistons have diametral slots 37 at both ends extending inwardly therefrom to permit the pistons to ride over the advanced knife 36'.

The seed potatoes, which it is desired to 65 cut into pieces suitable for planting in the

ground, are first placed on the inclined table 14 and the different sizes are preferably separated by hand and allowed to gravitate into the openings 18 and to drop into the chambers 20. Upon dropping into the 70 chambers 20 any dirt or loose matter adhering to the potatoes falls through the opening 21 and is taken away from the device in any suitable manner. The turning of the crank-shaft 29 causes a reciprocal movement of the 75 pistons 25, and when the pistons move forward in the chambers 20 all of the potatoes within the chambers are forced out of the chambers and through the tubes defined by the spring fingers 22. The pistons 25 force 80 the potatoes against the inner edges of the knives 36 36' which cut the potatoes into the desired number of pieces, the cut potatoes falling outwardly from the forward frame 13. The return movement of the pistons carries the potatoes which have subsequently fallen into the chambers 20 backward to the knives 36 and 36' and when the potatoes are cut the pieces fall outwardly from the 85 rear frame 13.

From the foregoing it will be seen that all 90 lost motion of the pistons 25 has been eliminated as both the forward and the return movements of the pistons operate to cut potatoes, making it possible to cut twice the 95 number of potatoes which would ordinarily be cut.

It is of course understood that various 100 changes and modifications may be made in the details of construction and design of the above specifically described embodiment of the invention without departing from the spirit thereof, such changes and modifications being restricted only by the scope of the following claims.

What is claimed is:

1. In a seed potato cutter, an inclined table 110 adapted to receive potatoes and having an opening at its lower end through which potatoes are adapted to fall, a frame adapted to hold said table in an inclined position, means for catching the potatoes falling through said openings, reciprocating pistons for forcing the potatoes outwardly from 115 said catching means, a pair of tubular members extending in opposite directions from said catching means, knives mounted in crossed relation to the ends of said tubular members, and pistons slidably mounted for reciprocating movement through the catching means and tubular members whereby potatoes may be moved out of the catching means first in one direction and then in the opposite direction and forced into engagement with the cutting knives.

2. A seed potato cutter comprising a 120 frame, an inclined table arranged upon the frame and adapted to receive potatoes for cutting, said table having an opening at its inner end, a tubular chamber having an 125

- opening in its upper surface for receiving potatoes falling through said opening in said table, open frames arranged in spaced relation to said chambers at opposite sides thereof, knives secured to said open frames, guide springs defining yieldable tubes arranged between said chamber and said open frames, and means movable through the chamber and yieldable tubes for forcing potatoes from said chamber through the tubes and into engagement with said knives so as to cut the potatoes into a predetermined number of pieces.
3. In a seed potato cutter, an inclined table having upstanding sides, a frame structure adapted to hold said inclined table, said table being secured at its lower end to said frame structure and having openings therein extending inwardly from said lower end, said openings being adapted to receive potatoes of various sizes, a plurality of chambers below said openings for catching the potatoes, a plurality of radially inclined resilient bars extending outwardly from said chambers and terminating at their outer ends in a plurality of supports, said bars being adapted to guide potatoes forced from said chambers, a plurality of horizontally disposed pistons mounted within said bars, a crosshead for normally holding said pistons in horizontal position, a bearing on said frame for said crosshead, a plurality of knives arranged on said supports in line with said pistons at opposite ends of said bars, and operating means for reciprocating said pistons in a horizontal direction between said knives for forcing potatoes into engagement therewith.
4. A seed potato cutter, comprising a frame, a plurality of receiving members for potatoes, a feeding table on the frame disposed in inclined position with its lower end over said receiving members and having openings registering with said members intermediate their ends, a plurality of vertical partitions disposed in the feeding table near its inner end and being spaced apart consecutively at increasing distances to accommodate potatoes varying in size and said openings corresponding to the width of said spaces, knives arranged in the opposite ends of said receiving members, and reciprocating pistons mounted in said receiving members and adapted to traverse said openings in the table whereby to alternately receive potatoes against the opposite ends of the pistons in said receiving members for forcing the potatoes against said knives.

PETER KNUDSEN.
